(57) **CLAIM**

The ornamental design for a pump for liquids, as shown and described.

DESCRIPTION

FIG. 1 is a front elevation view of a pump for liquids showing my new design;

FIG. 2 is a rear elevation view of the pump for liquids of FIG. 1;

FIG. 3 is a right side elevation view of the pump for liquids of FIG. 1;

FIG. 4 is a left side elevation view of the pump for liquids of FIG. 1;

FIG. 5 is a top plan view of the pump for liquids of FIG. 1;

FIG. 6 is a bottom plan view of the pump for liquids of FIG. 1; and,

FIG. 7 is a front, right perspective view from above of the pump for liquids of FIG. 1.

The portions shown in phantom (broken lines) are for illustrative purposes only and form no part of the claimed design.
